UNITED STATES PATENT OFFICE.

ALBERT L. EMENS, OF LA FAYETTE, INDIANA, ASSIGNOR TO DUNCAN ELECTRIC MANUFACTURING COMPANY, OF LA FAYETTE, INDIANA, A CORPORATION OF ILLINOIS.

INDUCTION ELECTRICITY METER.

Application filed December 24, 1926. Serial No. 156,880.

My invention, in general, relates to an induction electricity meter employing a supporting base having a forwardly projecting wall to constitute said base a chamber in which the current and pressure electro-magnets are disposed, a spindle rotatably supported upon said base in front of said magnets, and a metallic disc in inductive relation to said magnets.

10 My invention also relates, in particular, to an induction electricity meter employing a terminal chamber connected with and extending outwardly from the aforesaid wall and provided with a lid having means for holding it in closed position. Such a meter of the prior art was provided with a cover seated upon the front portion of the forwardly projecting wall of the base and serving to enclose the spindle, the damping magnet system, the counting train, and the spindle carrying the metallic disc or armature, these parts being located in front of the current and pressure electro-magnets of the meter. It was possible for a person desir-

20 ing to prevent the operation of such a meter for the purpose of obtaining current without cost to insert a strip of metal between the cover and its seat to an extent to engage the armature disc to prevent its rotation.

25 In accordance with my invention, I continue the cover skirt rearwardly of the front portion of the forwardly projecting wall of the meter base which is usually the place of engagement of the cover to prevent access 30 to the armature, this continued portion of the cover skirt preferably being upon the exterior of and surrounding the projecting wall of the meter base. Where the skirt continuation surrounds the forwardly projecting wall of the base it desirably extends

35 into close proximity to the terminal chamber to enable this chamber to cooperate with the cover skirt continuation for the purpose stated. The cover skirt continuation is desirably continued rearwardly beyond the front of the terminal chamber where it does not overlie the terminal chamber. The seat for the cover is not only guarded by the cover skirt in extending rearwardly thereof

40 but the cover skirt, being preferably of glass, guards against the drilling of holes where access could be had to moving meter parts.

45 I will explain my invention more fully by reference to the accompanying drawings in which Fig. 1 is a front elevation of a

meter with the cover thereon shown partially in elevation and partially in section with a portion broken away; Fig. 2 is a sectional view on line 2—2 of Fig. 1; Fig. 3 is a sectional view, on a larger scale, on line 3—3 of Fig. 1; and Fig. 4 is a perspective view of the cover.

The meter base is inclusive of a plate 1 formed with a forwardly projecting wall 2 to constitute a chamber, the base having a 65 perforated ear 3 extending from the top thereof for receiving a mounting screw 4 which is passed through the ear into the wall 5 or other support. Other screws 6 are passed through the lower portion of the 70 base into the support 5. The base is usually formed of iron and the chamber defined thereby is commonly closed by an iron wall 7 which is suitably joined to and within said 75 projecting wall 2. The pressure electro- magnet 8 and the current electro-magnet 9 are anchored to and upon the rear of the wall 7 by means of screws 10 passing through the cores of the electro-magnets into the wall 7, there being distance preserving 80 sleeves 11 surrounding the screws and interposed between the magnet cores and said wall. The electro-magnets are upon the rear side of the wall 7, being surrounded by the wall 2 and enclosed within the chamber 85 defined by said wall. The upright meter spindle 12 is positioned by the bearings 13 and 14 which are carried by the wall 7 upon the front thereof. The spindle carries a non-magnetic metallic armature disc 15 90 which extends through an opening 16 in the wall 7 and into the space between the poles of the magnets to be in inductive relation thereto. The spindle is provided with a worm 17 in mesh with the initial wheel 18 of a gear train which operates the indicators of the meter, in a manner well known. This gear train is supported by a permanent magnet 19 and this magnet in turn is held by the clips 20 which are carried by 95 100 the wall 7 and project forwardly from the wall 7.

A cover 21, commonly of glass, has a shoulder 22 which is seated upon the front portion of the wall 2, a sealing gasket 23 being interposed between the cover and said 105 wall. The skirt of the cover has a continuation 24 which extends sufficiently toward the rear of the meter base to prevent the insertion of a meter stopping implement past the shoulder 22. The terminal chamber 25 is 110

connected with and extends downwardly or outwardly from said wall 2, in accordance with common practice, this terminal chamber carrying the terminals for the electro-
5 magnets with which terminals the circuit wires 26 are also connected. The terminal chamber is provided with a lid 27 which is hinged or pivoted at 28 and fastened at 28'. Where the skirt continuation 24 is upon the
10 exterior of the meter, it closely approaches the front of the terminal chamber 25 which cooperates with the cover skirt portion 24 for the purpose stated. This cover skirt portion overlies said lid to aid in holding it closed and is elsewhere extended rearwardly of the front of the terminal chamber there to more effectively fulfill its purpose.

The cover is held in position by two rods 29 which are carried by the base and project 20 forwardly therefrom through the cover. Two nuts 30 are threaded upon these rods and press upon the cover to hold it upon its seat. The holes in the cover through which the rods 29 pass are inwardly flared at their 25 inner ends as indicated at 31. Bushings 32 are received in these holes and are furnished with flanges 33 at their outer ends against which the inner ends of the nuts 30 are pressed. Washers 34, preferably of felt, surround said bushings and are interposed 30 between the cover and said flanges. The inner ends of the bushings are flared or laterally extended, as indicated at 32', to fit the flaring inner ends of the holes in the cover through which the rods 29 are passed.

Having thus described my invention, I claim:

1. In an induction electricity meter, the combination with a supporting base having 40 a forwardly projecting wall to constitute said base a chamber; of a terminal chamber connected with and extending outwardly from said wall; current and pressure electro-
45 magnets disposed within the first chamber; a spindle rotatably supported upon said base in front of said magnets; a metallic disc upon said spindle and in inductive relation to said magnets; and a meter cover upon the base and having a skirt continuation ex-
50 surrounding said forwardly projecting wall and having one portion extending nearly to

the front of the terminal chamber and a remaining portion extending rearwardly beyond the front of said terminal chamber.

2. In an induction electricity meter, the 55 combination with a supporting base having a forwardly projecting wall to constitute said base a chamber; of a terminal chamber connected with and extending outwardly from said wall; current and pressure electro-
60 magnets disposed within the first chamber; a spindle rotatably supported upon said base in front of said magnets; a metallic disc upon said spindle and in inductive relation to said magnets; and a meter cover upon the base and having a skirt continuation 65 surrounding said forwardly projecting wall and having one portion extending nearly to the front of the terminal chamber.

3. In an induction electricity meter, the 70 combination with a supporting base having a forwardly projecting wall to constitute said base a chamber; of a terminal chamber connected with and extending outwardly from said wall; current and pressure electro-
75 magnets disposed within the chamber; a spindle rotatably supported upon said base in front of said magnets; a metallic disc upon said spindle and in inductive relation to said magnets; and a meter cover upon the 80 base and having a skirt continuation which has a portion extending rearwardly beyond the front of said terminal chamber.

4. In an induction electricity meter, the combination with a supporting base having 85 a forwardly projecting wall to constitute said base a chamber; of a terminal chamber connected with and extending outwardly from said wall; current and pressure electro-
90 magnets disposed within the chamber; a spindle rotatably supported upon said base in front of said magnets; a metallic disc upon said spindle and in inductive relation to said magnets; and a meter cover upon the base and having a skirt continuation ex-
95 tending rearwardly beyond the front of said projecting wall to the region of the terminal chamber.

In witness whereof, I hereunto subscribe my name.

ALBERT L. EMENS.
